ACETYLENE GENERATOR

Filed Feb. 18, 1939

UNITED STATES PATENT OFFICE

2,215,071

ACETYLENE GENERATOR

Malven Leonard Olson, Indianapolis, Ind., assignor
or to Oxweld Acetylene Company, a corporation
of West Virginia

Application February 18, 1939, Serial No. 257,091

17 Claims. (Cl. 48—19)

This invention relates to water-recession-type acetylene generators, and particularly to apparatus for preventing after-generation of acetylene when the generator is shut down.

5 Acetylene generators of this general type usually include an upright gas bell partially submerged within a quantity of water in a tank; and a calcium carbide holder mounted within the gas bell in position to expose carbide there-

10 in to the action of the water beneath the bell in accordance with the rate at which the generated gas is consumed. When the generator is shut down, the carbide within the holder is usually exposed to the water vapor above the body of

15 water as well as to contact with the water in the event that splashing occurs when the generator is moved. Accordingly, a useless after-generation of acetylene occurs which may cause serious trouble.

20 An object of this invention is to provide an acetylene generator of the water-recession type having simple, rugged and effective means for sealing the carbide holder from the action of the water vapor above the body of water within

25 the generator, as well as from water which may be splashed due to any movement of the generator; the provision of such a generator in which a pair of sealing elements are moved toward or away from each other by simply turning the gas

30 bell of the generator about its vertical axis relatively to the generator tank; the provision of such a generator in which the sealing means includes apparatus for supporting the carbide holder within the gas bell and means for moving the

35 supporting means axially relatively to the gas bell by turning the gas bell about its vertical axis relatively to the tank of the generator; and the provision of a gas bell, a residue baffle supporting the carbide holder, and means on

40 the gas bell adapted to cooperate with means on the baffle whereby the gas bell, the baffle, and the carbide holder, as a unit, may be removed from or placed within the tank of the generator.

45 The above and other objects and novel features of the invention will become apparent from the following specification and drawing in which:

Fig. 1 is a vertical sectional view, partly in elevation, of an acetylene gas generator to which the principles of this invention have been applied,—showing the parts in position to generate acetylene;

Fig. 2 is an elevational view, partly in section, of the generator of Fig. 1,—showing the parts in sealing relation; and

Fig. 3 is a sectional view taken along line 3—3 of Fig. 1.

Referring to the drawing, the invention is shown as embodied in a recession-type acetylene gas generator which comprises a water tank T, an upright gas bell B having a gas generating chamber G and a gas-collecting chamber K, and a carbide holder H positioned within and spaced from the side walls of the gas bell B. The tank T is normally filled with water to a height indicated by the dot-dash line L—L; and during operation, the water flows into or out of the generating chamber G of the bell B depending upon the gas pressure therein.

The calcium carbide holder H is located in the gas-collecting chamber K and is constructed to support a plurality of superimposed cakes R of calcium carbide in such a manner as to expose the lowermost cake to the action of the water. During gas generation, disintegration of the lower cake takes place, and the residue falls to the bottom of the water tank. As this action progresses the next succeeding cake gravitates to the bottom of the carbide holder and is consumed in the same manner.

The tank T comprises a substantially cylindrical shell 10, to the bottom of which is welded a base plate 12. In the present instance, the upper portion of the tank 10 is open to the atmosphere. The gas bell B comprises a lower bell portion 14, the diameter of which is slightly less than the inside diameter of the tank T thereby providing an annular passage for the flow of water from beneath the bell portion 14 to the outside thereof. The bell B includes an upper substantially cylindrical portion 16 of much smaller diameter than that of the portion 14. The upper portion 16 is adapted to extend above the top of the tank T and is provided with a pair of handles 17 and a pair of beads 18 rolled into the peripheral surface of said portion 16. The handles 17 are employed to turn the bell B about its vertical axis relatively to the tank T, and the pair of beads 18 are adapted to cooperate with a pair of yoke members Y for supporting the bell B at a fixed elevation with respect to the tank T, all to be more fully described later. The cylindrical portion 16 is adapted to extend below the point where the lower portion 14 is joined thereto, for the purpose of supporting a cylindrical resilient sleeve 20. The sleeve 20 is preferably made of rubber and it is rigidly and tightly connected to the end of member 16 by a strap and clamp 22.

The carbide holder H comprises an elongated

cylindrical container provided with a removable closure 23 at its top, and a perforate or basket portion 24 at its lower end capable of exposing the lower portion of the carbide to the action of water as the latter rises within the gas bell B. The holder H is also provided with a plurality of equally spaced longitudinally extending guiding grooves 26 adapted to guide and reduce the friction of the carbide cakes as they move downwardly therein, thus preventing them from tilting and consequently jamming within the holder. To support the carbide holder H, a plurality of circumferentially spaced metallic bars 28 depend from the basket portion of the carbide holder, extend substantially below the lowermost portion of the basket, then flare outwardly and are connected to a substantially cylindrical residue baffle 30. In addition to supporting carbide holder H, the baffle 30 also confines the residue as it falls from the basket 24 and directs the same into a residue receiver 32 on which baffle 30 rests. An imperforate substantially conical sealing element 34 is supported by rods 28 and is adapted to be moved into cooperating engagement with the sleeve 20 to form a moisture-tight seal between the water and the carbide in the holder H. This sealing function is attained while maintaining the gas bell B at a fixed elevation with respect to the tank T. In the present embodiment, this has been accomplished by providing cooperating means on the residue receiver 32 and the residue baffle 30 as well as on the baffle 30 and the bell B, all of which cooperate to elevate the sealing element 34 and carbide holder H when the gas bell B is turned about its vertical axis relatively to the tank T. For this purpose, the residue receiver 32 is provided with a series of cam surfaces 36 peripherally disposed about its upper edge, and the substantially cylindrical residue baffle 30 is provided with an equal number of fins 38 extending outwardly from the outer cylindrical surface thereof. The lower edges of the fins 38 are adapted to bear against and slide on the cammed edge of receiver 32 thereby raising and lowering the combined carbide holder H and residue baffle 30 and the sealing element 34, when relative turning of the baffle and receiver is effected.

In order to provide for relative turning movement between the baffle 30 and the receiver 32, the latter is held in a fixed position by welding it to the base plate 12 of the tank T, while the former is turned about its vertical axis when the bell B is turned about its vertical axis. The baffle 30 is slidably connected to and rotated by bell B through fins 38, each of which is adapted to move vertically between a pair of additional fins 40 mounted on the inner cylindrical surface of the lower portion 14 of the gas bell B (see Fig. 3). In the present embodiment of the invention, there are four diametrically opposed fins 38 connected to the outer cylindrical surface of the baffle 30, and four diametrically disposed pairs of spaced fins 40 connected to the inner cylindrical surface 65 of the lower portion 14 of bell B. There are also four diametrically disposed cam surfaces 36 located on the upper edge of the receiver 32, each of which is adapted to cooperate with the lower edge of one of the fins 38. The cam surfaces 36 comprise a flat portion 37, a gradually-inclined portion 39 and a second flat portion 41. Turning the gas bell B about its vertical axis relatively to the tank T will cause the baffle 30 to turn about its vertical axis, thus resulting in the 70 raising and lowering of the baffle 30, sealing cone

34, and carbide holder H. In this manner, the free end of sleeve 20 engages or disengages sealing cone 34 as the latter is raised or lowered.

The residue baffle 30 is additionally provided with diametrically opposed lugs 42 fixed to the outer periphery of said baffle. A pair of diametrically opposed cranks 44 are pivotally mounted along the outside of the lower portion 14 of the bell B. The lower extremity of the cranks 44 are formed into fingers 46 which, upon movement of the cranks 44 in one direction, pass beneath the lugs 42. Thus it is seen that means is provided between the bell B and the residue baffle 30 which will insure the removal from and the insertion within the tank T of the bell B, the carbide holder H, and the baffle 30 as a unitary assembly.

The yoke assembly Y comprises a pair of members 47 and 48, the central portions of which are formed to fit the outer surface of the upper portion 16 of the bell B in a manner to permit turning it about its vertical axis. The yokes 47 and 48 are rigidly secured together to provide a support for the pair of beads 48 to engage, and their outer ends are slightly spaced to form a slot for the reception of hinged nuts 47', which latter are secured to the top edge of the tank T. Spaced lugs 49 and 51 may be fixed to one of the members such as 47 between which a fin 53, fixed to the bell B, may move. The location of lugs 49 and 51 on member 47 is such that turning movement of the bell B, thereby moving fin 53 within the limit defined by their location, insures the cooperation between cam surface 36 and fins 38 to cause seating and unseating of sleeve 20 and cone 34. For convenience, the lug 49 may be marked "Operating" and the lug 51 marked "Seal."

Assuming that the generator has been in operation and the carbide has been entirely consumed, the procedure of recharging the generator and its operation is the following:

The wing nuts 47' are loosened and removed from their locking position. The bell B, carbide holder H, and baffle 30 are lifted from the tank T. Turning cranks 44 releases fingers 46 from engagement with lugs 42 and permits separation of the bell B from the carbide holder. The cap 23 is removed from the holder H and a new supply of carbide, preferably in the form of cakes, is deposited within the holder H. The cap 23 is replaced, the holder H is telescoped into the bell B, and the cranks 44 are turned to effect engagement of fingers 46 under lugs 42. The tank T is cleaned and filled to a predetermined level with fresh water. Likewise, the hydraulic valve V is refilled with fresh water. The assembly including the bell B, the holder H and the baffle 30 is inserted as a unit into the tank T, thus displacing the water to the level L—L, and the wing nuts 47' are then locked within the slots between members 47 and 48.

With the bell B in the position shown in Fig. 1, where fin 53 engages lug 49, generation of acetylene commences. When gas is generated within the generating chamber G of the bell B, it passes upwardly into the gas-collecting chamber K through a filter F into a back-pressure valve V, thence to an outlet O. Upon the generation of sufficient gas, the pressure within the chamber G increases beyond the pressure exerted on the surface of the water in tank T outside of the bell B, thereby causing the water to recede from the carbide within bell B to a point substantially below the bottom cake of carbide thus interrupting the generation of gas. When the pressure within

the bell B is lowered due to supplying acetylene to the gas-consuming devices, the water again rises in the bell and contacts the exposed carbide, thereby resuming generation of acetylene gas. 5 Thus, the amount of acetylene gas generated is automatically maintained to meet the demand.

When it is desired to shut down the generator for extended periods and safely store the remaining cakes of carbide in the holder H, it is only necessary to grasp the handles 17 and turn the bell B about its vertical axis relatively to the tank T until the fin 53 engages the lug 51 on yoke member 47 as shown in Fig. 2. This action causes the residue baffle 30, cone 34, and holder 15 H to move upwardly within tank T to a point where the top surface of the cone 34 engages the resilient lower edge of sleeve 20, thereby forming a water-tight seal between the water and the carbide within holder H. To resume generation it is only necessary to turn the bell B relatively to the tank T so that lug 53 abuts against lug 49 on member 47.

While the principles of the invention have been shown and described in detail to fully disclose one embodiment of the invention, it will be evident that numerous changes may be made in the details and certain features may be used without others, without departing from the principles of the invention.

30 What is claimed is:

1. An acetylene generator comprising, in combination, a tank adapted to contain water in its lower portion; an upright gas bell having an open lower end disposed below the normal water 35 level in said tank, said bell being supported within said tank at a fixed elevation but so that it may be turned about its vertical axis relatively to said tank; a calcium carbide holder adapted to expose carbide to the water within said tank; means for supporting said holder within said bell; a pair of sealing elements supported within said tank adjacent the lower end of said gas bell for forming a moisture-tight seal between the carbide in said holder and the water in said tank; and means actuated by said bell 40 when said bell is turned about its vertical axis relatively to said tank for causing said sealing elements to engage and thereby form such moisture-tight seal.

2. An acetylene generator as claimed in claim 50 1, in which a portion of the water within said tank and outside said bell is open to the atmosphere.

3. An acetylene generator as claimed in claim 55 1, in which said sealing elements are moved vertically and axially relatively to each other when said gas bell is turned about its vertical axis relatively to said tank.

4. An acetylene generator as claimed in claim 60 1, in which one of said sealing elements is supported at a fixed elevation with respect to the tank, and the other of said elements is moved vertically and into engagement with the first sealing element when said gas bell is turned about its vertical axis relatively to said tank.

5. An acetylene generator as claimed in claim 65 1, in which one of said sealing elements is connected to said gas bell and is adapted to surround the lower end of said carbide holder, and the other of said elements is moved axially toward or away from the element connected to said gas bell when said gas bell is turned about its vertical axis relatively to said tank.

6. An acetylene generator as claimed in claim 70 1, in which one of said sealing elements is con-

nected to said gas bell and is adapted to surround the lower end of said carbide holder, and the other of said elements is connected to said carbide holder, the latter of said elements being adapted to move vertically and axially relatively to said gas bell when said gas bell is turned about its vertical axis relatively to said tank. 5

7. An acetylene generator comprising, in combination, a tank adapted to contain water in its lower portion; a gas bell having an open lower end disposed below the normal water level in said tank, said bell being supported in an upright position within said tank at a fixed elevation but so that it may be turned about its vertical axis relatively to said tank; a calcium carbide holder within said gas bell adapted to expose carbide to the water within said tank; a multi-part residue baffle and receiver located in said tank and adapted to support said carbide holder; a pair of sealing elements respectively connected to said bell and said carbide holder; and cooperating means connected to said gas bell and multi-part baffle and receiver for moving said sealing elements toward and away from each other when said gas bell is turned about its vertical axis relatively to said tank. 10 15 20 25

8. An acetylene generator as claimed in claim 7, in which said multi-part residue baffle and receiver comprises a base member and a substantially cylindrical baffle member, said last-mentioned members having cooperating cam surfaces for raising and lowering said baffle member when said bell is turned about its vertical axis relatively to said tank. 30 35

9. An acetylene generator as claimed in claim 7, in which said cooperating means comprises cooperating cam surfaces on the residue baffle and receiver, and an axially slidible connection between said bell and residue baffle. 40

10. An acetylene generator as claimed in claim 7, in which said cooperating means includes cooperating cam surfaces on the components of said multi-part residue baffle and receiver, a portion of said cam surfaces being adapted to cause the closing of said sealing elements when said bell is turned about its vertical axis relatively to said tank, and a portion of which is adapted to maintain said elements in closed position upon continued turning of said bell in the same direction. 45 50

11. An acetylene generator as claimed in claim 7, in which said carbide holder is movable vertically, and in which one of said sealing elements comprises a resilient sleeve attached to said gas 55 bell and adapted to encircle the lower end of said carbide holder, and the other of said elements comprises a conical member fixed to said carbide holder directly beneath said resilient sleeve. 60

12. An acetylene generator as claimed in claim 7, in which said multi-part residue baffle and receiver includes a base element fixed to the bottom of said tank and provided with cam surfaces on its upper edge, and a substantially cylindrical member having spaced fins, the lower edges of which rest on the cam surfaces of said base element; said fins also being adapted to cooperate with pairs of spaced fins attached to said gas bell; said cylindrical member also being 70 provided with means adapted to cooperate with crank elements on said bell for removing and replacing said bell, holder, and cylindrical member within said tank as a unitary assembly. 75

13. An acetylene generator as claimed in claim 75

- 1, in which the carbide holder supporting means comprises a residue baffle adapted to be moved relatively to said bell, and in which said generator includes means mounted on said bell for detachably engaging said baffle, but constructed to provide for limited relative movement therebetween, whereby said bell and said baffle may be inserted within or withdrawn from said tank as a unitary assembly.
- 10 14. An acetylene generator as claimed in claim 1, in which the carbide holder supporting means comprises a residue baffle adapted to be moved relatively to said bell, and in which said generator includes means mounted on said bell for detachably engaging said baffle, but constructed to provide for limited relative movement therebetween, whereby said bell and said baffle may be inserted within or withdrawn from said tank as a unitary assembly, said last named means comprising manually operable cranks adapted to be rotated into and out of engagement with means on said baffle.
- 15 15. An acetylene generator as claimed in claim 7, and including means combining said holder and baffle, and means mounted on said bell for detachably engaging said combined holder and baffle but constructed to provide for limited relative movement between said bell and said com-

bined holder and baffle, whereby said bell and said combined holder and baffle may be inserted within or withdrawn from said tank as a unitary assembly.

16. An acetylene generator as claimed in claim 7, and including means associated with said baffle and said bell, adapted to limit movement of said baffle relatively to said bell and to detachably engage said bell with said baffle in order to permit unitary insertion and removal of said baffle, said holder, and said bell into and from said tank.

17. An acetylene generator as claimed in claim 1, in which the carbide holder supporting means comprises a residue baffle disposed beneath said holder and adapted to be moved relatively to said bell, and in which said generator includes cooperating means associated with said baffle and said bell, adapted to limit movement of said baffle relatively to said bell and to detachably engage said bell with said baffle in order to permit unitary insertion and removal of said baffle, said holder, and said bell into and from said tank, wherein said cooperating means comprises lugs on the exterior of said baffle and manually operable means on said bell adapted to detachably engage said lugs.

MALVEN LEONARD OLSON.
